DESIGN FOR A GAME BOARD

Hazel V. Walker, Caro, Mich.

Application October 7, 1940, Serial No. 95,675

Term of patent 14 years

To all whom it may concern:

Be it known that I, Hazel V. Walker, a citizen of the United States of America, residing at Caro, in the county of Tuscola and State of Michigan, have invented a new, original, and ornamental Design for a Game Board, of which the following is a specification, reference being had thereto in to the accompanying drawing, forming a part thereof, wherein:

I claim:

The ornamental design for a game board, substantially as shown.

HAZEL V. WALKER.
